UNITED STATES PATENT OFFICE

2,418,314

TROUSER HANGER AND STRETCHER

Milas A. Oxley, Kansas City, Mo.

Application April 10, 1944, Serial No. 530,327

1 Claim. (Cl. 223—63)

1

This invention relates to garment hangers of the character adapted to support in creased condition, the legs of trousers, and the primary aim is to provide an effective, rugged, and easily manipulable hanger that is inexpensive to manufacture and convenient to use.

One of the important aims of this invention is to provide a trouser hanger having uniquely arranged apparatus for moving the crease forming slats to and from a position where the legs of the trouser are taut and capable of being hung without slipping from the hanger.

Other objects of the invention include the provision of a garment hanger of the aforementioned character wherein the crease forming slats thereof are movable toward and from each other by a series of links arranged in pairs and disposed at related angles with respect to a tie bar, to the end that force in opposite direction on certain of the pairs of links will move the said slats to an operative condition.

This invention has for a still further aim, to provide in a trouser hanger of the aforementioned type, an unique and quickly manipulable latching means for the relatively movable parts, which means is disposed in a convenient position close to one end of the hanger, to the end that the operator may engage the movable part thereof with speed and dispatch.

Other objects of the invention include the manner of interengaging the several links of the hanger with the crease forming slats; the way in which the slats of the hanger and the tie bar thereof are maintained in the same plane; and the arrangement of a hanger hook upon the tie bar.

Other objects of the invention will appear during the course of the following specification, referring to the accompanying drawing, wherein:

Fig. 1 is a side elevational view of a trouser hanger and stretcher made in accordance with the present invention.

Fig. 2 is a perspective stretch-out view illustrating the manner in which the hanger supporting hook is secured to one end of the tie bar.

Fig. 3 is an enlarged fragmentary sectional view taken on line III—III of Fig. 1, looking in the direction of the arrow.

Fig. 4 is a similar detailed sectional view taken on line IV—IV of Fig. 1.

Fig. 5 is a sectional view taken on line V—V of Fig. 1; and

Fig. 6 is an enlarged fragmentary elevational view of a portion of a trouser hanger having

2

clamping elements made to embody a modified form of the invention.

Similar reference characters refer to like parts through the several views, and the numerals 10 and 12 indicate crease forming slats respectively, that are movable toward and from each other as the hanger is shifted from and to operative position within the tubular leg 14 of a pair of trousers.

Slat 12 has its outer edge contoured as at 16 to conform to the curvature of a pair of trousers along the portion thereof where the seat merges with the legs. The angle of divergence of the front and back creases of trouser leg 14 varies in some instances with the type of garment, and therefore, the pairs of links 18 are near one end of a tie bar 20, while a pair of links 22 are disposed adjacent to the outer ends of slats 10 and 12.

Links 18 are pivotally secured together and to tie bar 20 by a rivet or analogous means 24. The outer ends of the links have rebent tongues 26 formed thereon to pass through perforations 28 in slats 10 and 12, as the case may be. Such construction eliminates the necessity of an additional element at this point.

The outer ends of links 22 are likewise respectively attached to slats 10 and 12 through the medium of rebent tongues 30.

Tie bar 20 is longitudinally slotted as at 32 along a length thereof adjacent to its outer end and the inner ends of links 22 are secured to tie bar 20 through the medium of clamping elements, generally designated by the numeral 34, and clearly illustrated in Fig. 3.

In the preferred form of the invention, clamping elements 34 comprise a bolt 36 and a flat thumb nut 38, which may be manually manipulated to clamp links 22 against the opposite faces of tie bar 20.

The outer end of tie bar 20 carries a hook 40 pivotally journalled in barrel 42 of clip 44. This clip has a tongue 46 that projects through hole 48 in tie bar 20 and a pair of ears 50 are bent 45 against one face of bar 20 after tongue 46 has passed through hole 48. Thus, an effective hook, strong enough to support the weight of the trousers, is provided.

A clamping element of different specific character, is illustrated in Fig. 6. Tie bar 20 having slot 32 is the same as heretofore described, and links 22 are in the same relative position as links 22, illustrated in Fig. 1. In lieu of a threaded bolt 36, however, a rivet 100 having a head on each end thereof, pivotally carries a turn-button

102, the under surface whereof, rides along inclined arcuate bosses 104 to quickly draw links 22 against the opposite faces of bar 20—thus, a quick latching or clamping action may occur.

The placement of links 18 and 22 are as illustrated in Fig. 1, i. e. the pairs of links 18 have the elements thereof diverging outwardly and toward one end of the slats 10 and 12, while the links 22 diverge toward the opposite ends of slats 10 and 12 and outwardly. Slot 32 permits slats 10 and 12 to adjust themselves to the angularity of the crease of the trousers 14.

When the parts are in the collapsed position as shown in dotted lines of Fig. 1, slats 10 and 12 lie in the same plane as tie bar 20, and when the hanger is inserted to position, tie bar 20 is drawn in the direction of the upper arrow shown in Fig. 1, while inward pressure in the direction of the lower arrow, of that figure, is exerted upon the pair of links 22. Thus, pairs of links 18 force slats 10 and 12 outwardly at the same time as links 22 perform a similar function. Securing the clamping elements will prevent movement of the parts because of the angled disposition of the several pairs of links.

The material from which this article is constructed may be either light wood or metal, and while one form of the invention has been illustrated and described, it is obvious that modifi-

cations may be made without departing from the spirit of the invention or scope of the appended claim.

Having thus described the invention, what is claimed as new and desired to be secured by Letters Patent is:

In a trouser hanger of the kind having a pair of crease forming slats, pairs of links having their outer ends pivotally joined to the slats and their inner ends interconnected, and a slotted tie bar connecting the pairs of links; supporting means for said hanger comprising a clip on one end of the tie bar said clip having ears embracing said tie bar; a hook pivotally mounted on the clip; and means interconnecting the clip and the tie bar.

MILAS A. OXLEY.
